UNITED STATES PATENT OFFICE

2,476,182

DOOR CHECK

Howard M. Davidson, Detroit, Mich., assignor to
 Carey-McFall Company, Philadelphia, Pa., a
 corporation of Pennsylvania

Application September 24, 1946, Serial No. 698,894

2 Claims. (Cl. 16—86)

1

This invention relates to door checks for automobiles and the like; and particularly to what is known as the full open lock type, wherein the swinging motion of the door in opening is checked just prior to the door attaining its full open position, and wherein the swinging motion is completely arrested when the door attains its fully open position; and wherein the door is prevented from swinging out of its fully open position into a partially closed position unintentionally.

The virtue of the present invention lies in the simplicity and high efficiency of the structure and in the fact that substantially all the metal parts of the structure can be readily produced by die stamping from sheet metal and require no subsequent machining.

In the accompanying drawings:

Fig. 1 is a sectional plan view of a portion of an automobile body and door, with the door locked in its fully open position;

Fig. 2 is a view similar to Fig. 1 showing the door fully closed;

Fig. 3 is a vertical sectional elevation taken on the line 3—3, Fig. 1;

Fig. 4 is a transverse vertical sectional view taken on the line 4—4, Fig. 3;

Fig. 5 is a view similar to Fig. 4, showing the relative positions of the elements just prior to attaining the relationship shown therein;

Fig. 6 is a view similar to Fig. 1 showing a modification of the structure;

Fig. 7 is a rear elevation of the essential elements shown in Fig. 6; and

Fig. 8 illustrates the elements prior to attaining the relationship shown in Fig. 6.

As shown in Fig. 1, a portion of the hollow body of an automobile, adjacent the hinge side of a door thereof, is shown at A as comprising an outer plate a1, an inner plate a2 with a space x therebetween, and a transverse jamb plate a3 connecting the outer plate a1 and the inner plate a2 integrally.

A portion of the door B is illustrated as comprising an outer plate b1, an inner plate b2 and a side plate b3 connecting the inner and outer plates.

One of the door hinges is shown in broken lines at C. Operatively connecting the body A and the door B is a check link 1, one end of which is pivotally connected at 2 to a bracket 3 secured to the plate b3 of the door B.

The opposite end of the check link 1 passes through a horizontal slot 4 in the jamb plate a3 of the body A and is adapted to slide through a horizontal slot 5 in a check supporting plate 6

2

rigidly secured in the body space x behind the jamb plate a3 thereof.

The end of the check link 1, opposite the pivoted end of said link, is free and is formed as a T-shaped head 7 comprising a pair of ears 8, 8 respectively extending laterally in opposite directions from the body 9 of the link 1, at right angles to the longitudinal center line of the link 1.

Spaced inward of the link 1 from the ears 8, 8 along and projecting laterally in opposite directions from the opposite side edges 11, 11 of the link 1 is a pair of cam lugs 12, 12 which lie in the same plane as the ears 8, 8 and the body 9 of the link 1, with recesses 13, 13 between the ears 8, 8 and the cam lugs 12, 12 respectively.

The link 1 extends between a pair of pins 14, 14 which are provided at their opposite ends respectively with rubber or other resilient supports 15, 15 which, in the present instance, take a circular thick washer-like or bushing form, with each pair of the resilient supports 15, 15 spaced apart axially of an associated pin 14 and providing an annular groove 16 therebetween in which the link 1 is slidably mounted.

25 The pins 14, 14 and their associated resilient supports 15, 15 are confined in a suitable housing 17 which closely fits and prevents bodily movement of the resilient supports 15, 15.

The housing 17 is provided with laterally extending flanges 18, 18 which rest against and are secured to the plate 6 by rivets 19, 19 or the like.

Normally, the elements assume the relative positions shown in Fig. 2. As the door is opened, the link 1 is drawn through the housing, between the pins 14, 14, in the annular grooves 16, 16, until the cam lugs 12, 12 engage the pins 14, 14; whereupon continued outward movement of the link 1 causes the lugs 12, 12 to spread the pins 14, 14 and compress the portions of the resilient mountings 15, 15 lying outside said pins against the inside surface of the housing 17 until the lugs 12, 12 pass completely beyond the pins 14, 14. The resilient mountings 15, 15 then react to force the pins 14, 14 into the recesses 13, 13 in the link head 7. Immediately thereafter the ears 8, 8 engage the pins 14, 14 and arrest the outward movement of the link 1, thereby holding the door in its now fully opened position. The portions of the resilient mountings 15, 15 lying between the pins 14, 14 and the closure plate 20 lying between the housing 17 and the housing supporting plate 6 yield under the impact of the ears 8, 8 with the pins 14, 14 and dampens the

55 shock attending the engagement of the ears 8, 8

with the pins 14, 14, if and when the door B is swung open violently.

As shown in Fig. 6, the housing 17a is provided with trunnions 21, 21 pivotally mounted in brackets 22, 22 secured to the jamb plate a4 of the body A1, so that the pins 14a 14a will be disposed on a line at right angles to the longitudinal axis of the check line 1a at all times as the door B1 swings from a fully closed to a full open position and vice versa, thus avoiding any and all tendency for the link to bind as it moves through the housing 17a. The housing 17a is at all times self-aligning with respect to the link 1a.

I claim:

1. A door check comprising a flat elongated link, a housing having slots in opposite walls respectively for longitudinal movement of said link therethrough, check pins in said housing in engagement with opposite edges respectively of said link, rubber rings on opposite ends respectively of each pin with an annular recess therebetween and affording resilient mountings for said pins firmly confined in said housing, and lateral projections on the opposite edges respectively of said link for engagement with said pins when said link is moved longitudinally through said annular recesses.

2. A door check comprising an elongated link,

means for pivotally attaching one end of said link to a swinging door, a housing adapted for longitudinal movement of said link therethrough, means for pivotally supporting said housing adjacent said door, check pins in said housing in engagement with opposite edges respectively of said link, annular resilient mountings for said pins embracing the same at respectively opposite sides of the link and firmly confined in said housing, relatively spaced cams and stop ears on opposite edges of said link to engage said pins and compress said mountings during longitudinal movement of said link through said housing.
